UNITED STATES PATENT OFFICE.

GEORGE BAEHR, OF MCKEESPORT, AND HARRY B. LYNCH, OF VERSAILLES, PENNSYLVANIA, ASSIGNORS TO NATIONAL TUBE COMPANY, OF PITTSBURG, PENNSYLVANIA, A CORPORATION OF NEW JERSEY.

MAGNETIC DRAWING APPARATUS FOR PIPES, &c.

No. 857,856.

Specification of Letters Patent.

Patented June 25, 1907.

Application filed February 25, 1907. Serial No. 359,185.

To all whom it may concern:

Be it known that we, GEORGE BAEHR, of McKeesport, Allegheny county, Pennsylvania, and HARRY B. LYNCH, of Versailles, Allegheny county, Pennsylvania, have invented a Magnetic Drawing Apparatus for Pipes and other Objects, of which the following is a full, clear, and exact description, reference being had to the accompanying drawings, forming part of this specification, in which—

Figure 1 is a side elevation, partly in section of drawing apparatus embodying our invention; Fig. 2 is a plan view of the upper portion of the same showing the actuating motor; Fig. 3 is a plan view of the lower portion of the same, and showing the carriage or trolley; Fig. 4 is a view similar to Fig. 1, but showing a modification; Fig. 5 is an end view of one form of magnet; Fig. 6 is a side view of the same partly broken away; and Fig. 7 is a wiring diagram of the motor and magnet coils and the controlling switches therefor.

Our invention has relation to magnetic drawing apparatus, and although useful for other purposes, is particularly designed for use in drawing pipes in bundles or bunches from tanks or other receptacles.

The object of our invention is to provide means whereby either a small or a large number of pipes or other articles may be simultaneously withdrawn from a tank or elsewhere by the action of a magnet; and our invention consists in the novel construction, arrangement and combination of parts all substantially as hereinafter described.

Referring to the accompanying drawings, the numeral 2 designates a track or run-way whose upper end is pivoted at 3 to a wall or other support 4, and whose lower end portion overhangs a tank 5, its intermediate portion having supports 4^a. The track or run-way may be conveniently formed by an I-beam, the flanges of which form tracks for the wheels 6 of a carriage or trolley 7 consisting of side frames having bearings 8 in which the shafts 9 of the wheels 6 are journaled.

Supported by depending portions of the trolley frame is a lifting magnet 10 to which is connected a cable 11 which is in turn con-

nected to a winding drum 12 at the upper portion of the run-way. This drum 12 is arranged to be actuated by an electric motor 13 through the train of gear 14, 15, 16, 17, 18 and 19. The magnet 10 is energized by the coils 20 on the core 21. The lifting face of the magnet is preferably composed of a series of pole pieces 22 of alternate polarity, as shown in Fig. 5, the air gaps between adjacent pole pieces being of less width than the diameter of the pieces to be lifted. This construction provides a magnet which is especially adapted to the purpose, owing to the approximately uniform distribution of the lines of magnetic force through the several pole pieces, and owing to the narrow air gaps which prevent the ends of the pieces from entering between the pole pieces. Other forms of magnets may, however, be employed.

23 designates a clamping plate of magnetic material which is pivoted to the magnet at 24, and is designed to be attracted thereby so as to bind upon the series of pipes and assist the lifting action of the magnet. 25 is a stationary trip piece secured to the track or run-way 2 near its lower end for the purpose of throwing this clamp 23 upwardly to permit the magnet to engage the ends of the pipe, as shown in Fig. 1. As soon as the carriage starts to move up on the run-way, the short arm of the clamping plate which has been in engagement with this trip moves out of contact therewith, and the magnetic force of the magnet brings the clamping plate into contact with the top of the bundle of pipes.

26 is a buffer spring and 27 a follower seated against such spring, and arranged to be engaged by the carriage 7 to check its downward movement.

28 is an apron of non-magnetic material which is secured to the lifting end of the magnet, and which forms a support for the end portions of the pipes being lifted.

29 designates a hinged stop device secured to the track 2 near its upper end. This device is arranged to permit the frame of the trolley carriage to pass thereunder in its upward movement, in case the operator should not stop the motor in time, but will drop back to form a lock to prevent the descent of the carriage.

30 indicates a roller or other support be-

low the runway, actuated by a power cylinder 31, and upon which the pipes are arranged to be lowered when they are disengaged from the magnet.

5 32 indicates the wires or conductors strung along the track 2 by means of which the magnet coils are energized, said wires or conductors being engaged by trolleys 33.

The operation of the device is as follows:—
10 The carriage 7 is run down the track to the position indicated in Fig. 1. The bundle of pipes in the tank is then raised by any usual means, (such as the lifting device 34 shown in Fig. 4) into position to be attracted by the
15 magnet. The motor 13 is then operated to wind up the cable 11 and draw the carriage upwardly on the track, thereby drawing the bundle of pipes out of the tank. The roll or support 30 is then raised and the pipes
20 drop thereon by de-energizing the magnet coils.

In the modification shown in Fig. 4, the track or run-way 2^a is shown as pivoted at 2^b, its upper end being adjustably guided as
25 shown at 35. A motor 36 mounted upon a stand or support 37 is geared to a crank shaft 38 whose crank 39 is connected by link 40 with the track or run-way at the point 41. In this modification after the pipes have been
30 engaged with the magnet and are being drawn out of the tank, the motor 36 is actuated to swing the run-way on the pivot 2^b to a substantially horizontal position to facilitate the dropping of the pipes onto a
35 conveyor 42.

In Fig. 7, I have shown a wiring diagram of the motor and magnet coils. In this diagram 43 designates the armature of a compound-wound motor, 44 the series field coils, 40 45 the shunt field coils, and 46 the coils of the usual solenoid brake 47 of the motor. The controller shown is a double voltage controller having connections with the line wires 48, 49, 50 and 51 having differential
45 voltages such as indicated. The movable arm 52 of the controlling switch has two positions, an up position, and a down position, whereby different speeds of the motor may be obtained, it being desirable to run
50 the motor on a higher voltage while the carriage is moving downwardly to the lower end of the track.

53 designates the relatively-fixed contacts of the magnet switch or controller, 54 a group of relatively-movable contacts and 55 a second group of relatively-movable contacts. The contacts 53 and 54 when engaged connect the magnet coils 20 in circuit between the line wires 48 and 51, while the
55 contacts 53 and 55 when engaged with each other, short circuit the coils 20 through the lamps 56 or other non-inductive resistance to prevent inductive kick of the coils 20.

We do not, however, limit ourselves to the
65 use of any particular controlling means for the

magnet, and any suitable type of motor controlling device therefor may be employed.

The advantages of our invention result from the use of pipe drawing apparatus having a lifting magnet arranged for contact with the ends of the pieces to be lifted. These may be pipes, rods, bars, or structural or other shapes of magnetic metal.

The apparatus described forms a simple and conveniently operated means by which 75 pipes or other articles may be rapidly handled in large quantities.

Various changes may be made without departing from the spirit and scope of our invention. Thus, the form of runway, the 80 manner of supporting the same, the details of the magnet carriage, and the arrangement of the operating motor and gearing therefor, may be changed in various ways.

We claim:—

1. In apparatus for drawing or pulling pipes or other objects in an endwise direction, a track-way, a carriage mounted to travel thereon, and a magnet carried by the carriage and having its polar surface in a plane 90 substantially at right angles to the length of the track-way; substantially as described.

2. In apparatus for drawing or pulling pipes or other objects in an endwise direction, an inclined track-way, a carriage or trolley 95 mounted for travel on the track-way, and an electro-magnet carried by the carriage or trolley and depending therefrom, said magnet having its polar surface in a plane substantially at right angles to the longitudinal 100 plane of the track-way; substantially as described.

3. In apparatus for the purpose described, a track-way, a carriage mounted for travel thereon, and an electro-magnet rigidly secured to the carriage; substantially as described.

4. In apparatus for the purpose described, a track-way, a carriage or trolley mounted for travel thereon, an electro-magnet carried 110 by the carriage or trolley and having its polar surface in a plane substantially at right angles to the plane of the track-way, a motor for operating the carriage or trolley, and means for controlling the speed of the motor; 115 substantially as described.

5. In drawing apparatus, a pivoted track or run-way, means for moving the track or run-way on its pivot to change its angular position, a carriage mounted thereon, and a magnet suspended from the carriage; substantially as described.

6. In apparatus for the purpose described, a movable carriage having a magnet suspended therefrom, said magnet having a 125 pivotal magnetic clamping member; substantially as described.

7. In apparatus for the purpose described, a movable carriage, a magnet carried thereby, and an apron of non-magnetic material se- 130

cured to the lifting end of the magnet, and arranged to form a support for the end portions of a plurality of pipes or other articles; substantially as described.

5. 8. In apparatus for the purpose described, a lifting magnet having a clamping piece of magnetic material pivoted thereto; substantially as described.

In testimony whereof, we have hereunto set our hands.

GEORGE BAEHR.
HARRY B. LYNCH.
